UNITED STATES PATENT OFFICE.

JEROME B. SECOR, OF DERBY, CONNECTICUT, ASSIGNOR, BY MESNE ASSIGNMENTS, TO SECOR TYPEWRITER COMPANY, OF DERBY, CONNECTICUT, A CORPORATION OF CONNECTICUT.

RIBBON FEED AND MOVEMENT MECHANISM.

1,033,124.

Specification of Letters Patent.

Patented July 23, 1912.

Application filed August 5, 1904. Serial No. 219,607.

To all whom it may concern:

Be it known that I, JEROME B. SECOR, a citizen of the United States, residing at Derby, in the county of New Haven and State of Connecticut, have invented certain new and useful Improvements in Ribbon Feed and Movement Mechanism, of which the following is a specification.

The object of my invention is to provide a ribbon feeding mechanism for that class of typewriting machines known as front strike machines in which the ribbon is fed step by step upon each actuation of the type bars and in which the ribbon is moved upon each operation of a type bar to the printing point to receive the type head impact.

My invention is furthermore applicable to a typewriting machine in which the platen is shifted to change the "case" of the type and for which purpose I have provided an improved means whereby, upon changing the printing "case," the ribbon will be shifted to a different initial point so that upon actuation of the type bars, the ribbon will always be brought to the proper printing position.

In a machine involving my invention is embodied a pair of ribbon spools, one at each side of the machine and carrying individual feed devices suitably connected to and actuated by the type bar actuating mechanism. Relating to this portion of the machine, my invention comprehends an improved means whereby the reversal of the direction of feed of the ribbon is brought about consisting in a suitable connection between the individual ribbon feed devices, by which only one of said devices will operate at a time and through which one of said feeding devices is thrown out while the other is thrown into operation.

My invention furthermore relates to many improved details of structure incidental to the above named improvements which will hereinafter be made clear and are shown in the accompanying drawings, in which like reference numerals refer to like parts and in which—

Figure 1 is a transverse section through a front strike typewriting machine, parts of the ribbon feeding mechanism being removed and showing especially my improved ribbon movement mechanism and its connec-

tion with the type key and platen shift levers. Fig. 2 is a detail perspective view 55 of a bracket and a depressible frame pivoted therein forming part of the ribbon movement mechanism. Fig. 3 is a detail side elevation of the ribbon vibrating levers showing means operating same and showing the same 60 in contracted positions. Fig. 4 is a similar view showing same in extended positions when operated by the platen shift mechanism. Fig. 5 is a like view when operated through the universal bar. Fig. 6 is a detail 65 elevation, looking in a direction opposite to Fig. 1, and showing the overlapping ribbon vibrating levers, the bracket upon which they are pivoted and a means for actuating said levers. Fig. 7 is a detail front elevation of the ribbon frisket and alining plate 70 upon which the same is mounted. Fig. 8 is a bottom plan view of the individual ribbon winding or actuating devices showing the parts of one of said devices in operative engagement and parts of the other of said devices out of operative engagement and showing the means for actuating said devices. Fig. 9 is a detail side elevation of one of the 75 devices shown in Fig. 8. Fig. 10 is a detail 80 sectional view through one of the ribbon spools showing the connection with its rotating shaft and showing the ribbon leading from such spool. Fig. 11 is a side elevation of a slightly modified form of means for operating the ribbon vibrating levers. Fig. 12 is a detail side elevation of a portion of the 85 same. Fig. 13 is a top plan view of the same. Fig. 14 is a detail elevation of a portion of the structure shown in Fig. 10, showing the 90 same in operative engagement with the ribbon feed devices; and Fig. 15 is a detail view illustrating a modified form of ribbon vibrating lever.

Referring now in detail to the drawings: 95 1 represents the frame of the machine having mounted thereon a fulcrum bar 2 at the rear of the machine upon which the key levers 3 are fulcrumed. Key levers 3 are held normally in elevated position by coil 100 springs 4 secured to the heel of the levers 3 at one end and secured at their other ends to a portion of the machine frame. Mounted above the key levers 3 on brackets 5 on the bridge 6 of the machine are pivoted a 105 series of type bars 7 arranged in a segment,

and to which are connected at their heels the straddle links 8. Straddle links 8 are connected at their forward ends to the upper arms of bell cranks 9 pivotally mounted on suitable brackets 10 on a bar 11 extending transverse the machine. The lower arms of bell cranks 9 are engaged by downwardly extending straddle links 12 which are connected at their lower ends to the key levers 13. A depression of any one of the key levers 13 will draw its straddle link 12 downwardly, depressing the forward arm of the bell crank 9, drawing the straddle link 8 forward to throw the type bar 7 to the printing point. The return of the straddle links 8 to their normal position is accelerated by coil springs 13 secured at one end to a portion of the bridge 6 and at their other ends to a projection on the straddle link 8. Carried by each of the straddle links 8 is a pivoted hooked arm 14 resting upon a universal bar 15 carried by a frame 16. Frame 16 is suitably mounted upon a shaft 17 extending transverse the machine. Engagement of the universal bar 15 by the hooked arm 14 upon each actuation of a straddle link 8 will rock the frame 16 which being rigidly mounted upon the shaft 17 will rock the said shaft. (Fig. 1.)

All of the mechanism thus far described is clearly shown and described in my application filed August 7th, 1903 for improvements in typewriting machines, Serial No. 168600.

Shaft 17 has rigidly mounted thereon at each side of the machine a downwardly depending arm 18.

19 are the ribbon-spool shafts having at their upper ends a bevel gear 20 adapted to mesh with a bevel gear 21 on the ribbon spool carriers 22 mounted on pins or projections 23 rigidly seated in the top of the machine frame 1. Spools 22' are mounted on carriers 22. The pins or projections 23 upon which the spool carriers 22 are mounted are set at a slant to offset the spools from the carriage and to provide the proper feed slant for the ribbon in both its upper and lower case positions. (Fig. 10.) At the lower end of each of the shafts 19 is rigidly mounted a ratchet wheel 24, and loosely mounted on each of the said shafts is a bell crank lever 25 carrying at one end antifriction rollers 26 adapted to be moved by means hereinafter described into and out of the path of vibration of the downwardly extending arm 18. At its other end the bell crank 25 carries a pawl 27 pivotally mounted on said bell crank and held normally in engagement with the teeth of the ratchet wheel 24 by a spring 28. The shafts 19 are seated in brackets 29 mounted upon the machine base, and bell cranks 25 are connected to the brackets 29 by coil springs 30, coil springs 30 tending to hold the bell cranks

25 in a position which will bring their antifriction rollers 26 into the path of vibration of the arm 18.

34 is a dog mounted pivotally on brackets 29, held in engagement with the teeth of ratchets 24 by a spring 34' and adapted to prevent movement of said ratchets in the wrong direction.

It will be readily seen that each time an arm 18 engages an antifriction roller 26 on the bell cranks 25, the said bell cranks 25 will be displaced in opposition to the coil springs 30 which tend to hold the rollers 26 in the path of arms 18 and ratchet wheel 24 will be rotated, and, through the mechanism 80 already described, the spool 22 mounted upon the shaft 17 rotated, will be rotated to wind the ribbon upon that spool.

In order to throw one of the pawls 27 out of engagement with the teeth of its ratchet wheel 24 while the other pawl 27 is being actuated, I have provided a segmental cam plate 31 mounted on each of the shafts 19 above the bell crank 25 and bracket 29, and having cam projections or surfaces 32 adapted to ride under the pawl 27, and 33 adapted to ride under the pivoted dog 34 and carry the same out of engagement with the teeth of ratchet 24 in opposition to spring 34'. Cam plate 31 is provided with an arm or projection 35 to which is connected a link 36, connected at the other end to the arm or projection 35 on the opposite cam plate 31. One of the cam plates 31 is provided with a thumb piece or projection 37 by which the cam plates 31 may be adjusted to throw the pawl 27 and dog 34 of one of the ratchet wheels 24 into engagement, and the pawl 27 of the other ratchet wheel 24 out of engagement, for the purpose of reversing the feed of the ribbon. The cam plates 31 are so connected by the links 36 that oscillation of one of said cam plates to bring its pawl 27 into engagement with the teeth of the ratchet wheel 24 will throw the pawl 27 of the opposite cam plate 31 out of engagement with the teeth of its ratchet wheel 24. (Fig. 8.)

On each of the cam plates 31 is a projection 25' adapted either to engage and move bell cranks 25 in opposition to springs 30 to take rollers 26 out of the path of engagement at the same time that cam surfaces 32, 33 ride under pawl 27 and dog 34 respectively or to allow the roller 26 to be drawn into the path of engagement at the same time that pawl 27 and dog 34 are lowered into engagement with the teeth of the ratchet wheel 24. Each of the brackets 29 is provided with a stop 26' against which the rollers 26 abut normally, the function of these stops being to prevent said rollers 26 from going beyond the path of reciprocation of arms 18.

I have now described the means for rotat-

ing the spools. The ribbon is wound upon the spools 22' (Fig. 10) and passed from one spool through a frisket 43 slidably mounted upon the alining plate 44. (Fig. 1.)

For the purpose of moving the frisket to and from the printing point upon each actuation of a type bar, and for the purpose of shifting said frisket to an advanced initial point upon actuation of either of the platen shift levers, I have provided the following mechanism: positioned on the bar 11 is a bracket 45, in which is pivoted a U-shaped frame 46, (Fig. 2) carrying at its free end a U-shaped link 47, through the free ends of which is passed a pin 48 projecting from said link 47. Frame 46 is provided with a pin 49 through its sides and projecting to one side of said frame 46, and in direction opposite to the pin 48. Both pins 48 and 49 may carry antifriction rollers. 50 is a forked arm on a bar 51 connecting a pair of platen shift sub-levers 52, which are pivoted at 53 on the machine frame. Levers 52 engage at their rear ends a platen elevating frame 54. Levers 52 are connected by straddle links 55 to main shaft key levers 56, which are rigidly mounted at their rear ends on a rock shaft and held in raised position by the usual spring means, said rock shaft and spring means not being shown in the drawings. Levers 56 being mounted rigidly upon the rock shaft, move in unison. Bracket 45 is provided with an arm or extension in which is seated a pivot pin 57. (Fig. 6.) Pivoted on pin 57 is a ribbon vibrating lever 58, one arm of which is connected to a bent pitman 59 engaging a perforation 60 in the frisket 43, and a slot 61 in the alining plate 44, which limits the movement of said pitman. The other arm of the lever 58 is provided with a notch 62 engaging the pin 48 and a portion of the engaging surface of which is angular to the path of travel of the pin 48 in one direction 45 to form a cam so that upon movement of pin 48 in either direction permitted by its link 47 the lever 58 will be displaced to move the pitman 59. Hung to pin 57 is a second ribbon vibrating lever 63 overlapping lever 58 and provided with a notch 64 in one arm thereof, engaging pin 48. The other arm of the lever 63 is engaged by a projection 65 mounted on an arm 66 rigidly mounted on the shaft 17. Projection 65, upon movement of the arm 66 by shaft 17 displaces the lever 63 moving pin 48, and link 47 on its pivot and laterally forcing said pin against the side of the notch 62, the lever 58, in order to compensate for said lateral movement of the pin 48 being forced to turn on its pivot 57, and thus moving the pitman 59 as the shaft 17 is oscillated upon each actuation of a type bar. Through this means the pitman 59 is moved upon each actuation of a type bar. The move-

ment of lever 63 by projection 65 is limited by a stop 67 (Fig. 6) on bracket 45 engaging a notch 68 on lever 63. If shift key 56 be operated, turning the shift sub-levers 52 on their pivots, the frame 46 through the pin 49 and forked arm 50 of the bar 51, will be displaced, moving pin 48 in a direction transverse to the direction in which said pin was moved by lever 63 against the angular edge of the notch 62, the effect of which will be to displace lever 58 moving the pitman 59 and carrying the frisket 43 to an advanced initial point in its reciprocation. A subsequent actuation of any one of the type bars will displace the pin 48 laterally in the manner already described, and therefore displace or move the lever 58 on its pivot 57 to move the pitman 59 and the bracket 45 to the advanced printing point. Hence it will be seen that the device is operative in both of the "case" positions of the platen and that upon the shifting of the platen the frisket is shifted to an advanced initial point. In order to prevent the lever 63 from being displaced by the pin 48 when the latter is moved through the platen shift mechanism, a portion of the bracket 45 is bent outwardly into the path of the lower arm of the lever 63 to form a stop 65' so that the lever will engage the same immediately upon movement of the pin 48 by the platen shift mechanism, and its displacement by the said pin 48 will be prevented which will have the effect of maintaining the pin 48 in its proper path against the angular portion of the notch 62 to elevate the frisket as desired.

In Figs. 11, 12 and 13, I have shown slight modifications in the mechanism just described for operating the ribbon vibrating levers. Therein I have shown a means for operating the lever 63 by the key bars 3 instead of by the hooked arms 14 carried by the straddle links 8. For this purpose I construct the bracket 45 with an upwardly projecting arm 69 which carries a pivot pin 70 on which is pivoted a bell crank 71 carrying on its lower arm an antifriction roller 72 engaging a notch 73 in the upper arm of the lever 63. Pivoted to the upper arm 70 of the bell crank 71 is a depending rod or link 74 which is connected at its lower end to an arm 75 on a depression frame 38. The depressible frame 38 is pivoted at 39 to the sides of the machine frame 1 and carries at its upper end a rotatable universal bar 40, this bar 40 being a substitute for the universal bar 15 carried by the arm 16. This universal bar 40 is located and held in engagement on the under sides of the key levers 3 by spring or springs 41 secured at their lower ends to the frame 38 and their upper ends to a portion of the machine frame. Upon each depression of a key lever 3, the universal bar 40 is forced down

turning the depressible frame 38 upon its pivots drawing the rod 74 downwardly, turning the bell crank 71 on its pivot 70 and depressing the lever 63 to elevate the pitman 59 through the notch 64, pin 48 and the notch 62 in the lever 58.

In Fig. 14 is shown a slight modification in the means already described for actuating the bell crank 25 carrying the pawls 27 to effect the rotation of the ribbon shafts 19. A pair of projecting cam fingers 42 mounted on the frame 38 and adapted to engage the antifriction rollers 26 on the bell cranks 25 in the same manner as the arm 18 hereinbefore described except that such rollers 26 are in this structure changed to vertical position to meet the thrust of the finger 42, which, being mounted upon the vertically depressible frame 38 travels in a vertical plane.

If desired, as shown in Fig. 15, the overlapping ribbon vibrating levers may be modified by doing away with one wall of the notches 62, 64, that is by constructing the lever so that the pin 48 will engage the edge of the notches in said levers. The levers being overlapping and hung to the same pivot 57 in this modified structure the pin 48 engages the opposite edges of said levers, the engaging edge of the lever 63 being straight while the engaging edge of the lever 58 is angular and the operation being identical in principle to the operation of the notched levers and quite as effective.

I do not desire to limit myself to the construction shown and described herein but the same may be varied without departing from the spirit and scope of my invention.

Having thus described my invention, the following is what I claim as new therein and desire to secure by Letters Patent:—

1. In a writing machine, the combination with the ribbon spool and the shaft geared thereto, of a ratchet wheel rigidly mounted on said shaft, a bell crank loosely mounted on said shaft, the pawl carried by the said bell crank and in engagement with the teeth of the ratchet wheel, the rock shaft suitably mounted in the machine frame, the universal bar mounted on the said rock shaft and adapted to rock the same, the downwardly extending arm mounted on the said rock shaft and adapted to engage and displace the said bell crank to feed the said ratchet wheel, and cam means for disengaging the said pawl from the teeth of the said ratchet wheel.

2. In a writing machine, the combination with the ribbon spool and the shaft geared thereto, of a ratchet wheel rigidly mounted on the said shaft, a bell crank lever loosely mounted on said shaft, a pawl carried by said bell crank in engagement with the teeth of said ratchet wheel, a depressible frame mounted beneath the key levers, a cam fin-

ger or projection on the said frame in position to engage and displace the said bell crank upon depression of the frame, a spring for returning said bell crank to its normal position, and cam means for throwing the said pawl out of engagement with the teeth of said ratchet wheel, and then throwing said bell crank out of the path of said finger or projection.

3. In a writing machine, the combination with a frisket and a pitman connected to and adapted to elevate said frisket, of a lever connected to said pitman and having a cam face thereon, a pin mounted in engagement with said face, means actuated by the platen shift mechanism, and means actuated by the type-bar actuating mechanism for depressing said pin to elevate the said lever to bring the frisket to proper printing position.

4. In a writing machine, the combination with a frisket, of a lever connected to and adapted to shift said frisket and having a cam surface, a pin connected to and shifted by the platen shift mechanism and engaging said surface, a depressible frame located beneath the key bars, a lever overlapping said frisket shift lever, having a notch therein engaging the said pin, and suitable pivotal connection between the depressible frame and the last named lever.

5. In a writing machine, the combination with a frisket, of a frisket shift lever having a cam surface therein, a second lever overlapping said frisket shift lever having a notch therein, a pin connected to the platen shift mechanism and engaging the cam surface and the notch in the second lever, a depressible frame located beneath the key bars, a bell crank lever pivotally mounted adjacent the second lever, an anti-friction roller mounted on the bell crank lever, a notch in said second lever engaging said antifriction roller, and a link connecting said bell crank lever to said depressible frame.

6. In a writing machine, the combination with a frisket, of a frisket shift lever having a cam surface, connection between said frisket and said lever, a bracket mounted on the machine frame to which said frisket shift lever is pivoted, a cam lever overlapping said frisket shift lever and pivoted to the said frame, a bell crank lever also pivoted to the said bracket, an antifriction roller carried by said bell crank lever and engaging a notch in the said cam lever, a depressible frame located beneath the key bars, and a link connecting the bell crank lever to the said frame.

7. In a machine of the character described, the combination with the ribbon spool, a shaft for said spool, a ratchet for said shaft and a universal bar, of a horizontal bell crank lever, a pawl carried by said

- lever, an antifriction device on said lever, and a downwardly depending arm operated by the universal bar to engage said antifriction device and actuate said lever.
8. In a machine of the character described, the combination with the ribbon frisket, a frisket actuating lever having a cam surface, a stud for engaging said surface, type-key actuated means for displacing said stud in one direction, and means for displacing said stud in another direction to actuate said frisket shifting lever.
9. A ribbon mechanism for type-writing machines comprising a shiftable ribbon support, means including adjacently disposed cam members and an interposed roller for actuating said support by character printing keys, a key independent of said printing keys and connections controlled thereby and operatively connected to said cam roller to adapt the support actuating means to different ranges of action preparatory to printing.
10. A ribbon mechanism for typewriting machines comprising a shiftable ribbon support, support actuating means including relatively movable members provided with adjacent cam surfaces, character printing keys operably connected to one of said cam members, a coöperating member intervening said cam members and normally movable therewith, a key other than said printing keys operably connected to said intervening member, the last said key being movable transversely to said normal movement, to vary the initial position of the ribbon preparatory to printing.
11. In a typewriting machine, the combination of a ribbon vibrator, two ribbon vibrator actuating levers having substantially parallel arms, an intermediate connection between said substantially parallel arms, and means for shifting the connection relatively to said levers and longitudinally of said parallel arms.
12. In a typewriting machine, the combination of a ribbon vibrator, two ribbon vibrator actuating levers having substantially parallel arms, an intermediate connection between said substantially parallel arms, a platen, platen shifting means and means under control of said platen shifting means for shifting said connection longitudinally of said substantially parallel arms.
13. In a typewriting machine, the combination of a ribbon vibrator, a universal bar, intermediate angular levers between said universal bar and vibrator, said angular levers being mounted on fixed axes, a connection between said angular levers, and means for shifting said connection relatively to said levers.
14. In a typewriting machine, the combination of a ribbon vibrator, a universal bar, intermediate angular levers between
- said universal bar and vibrator, a platen, platen shifting means, and means under control of the platen shifting means for shifting said connection relatively to said levers. 70
15. In a typewriting machine, the combination of a ribbon vibrator, vibrator actuating levers having substantially parallel arms slotted longitudinally thereof, a connecting device engaging the slotted parallel arms of said actuating levers and movable longitudinally of the slotted arms, and means for effecting a movement of said connecting device longitudinally of the slotted arms of said levers. 75
16. In a typewriting machine, the combination of a ribbon vibrator, vibrator actuating levers having substantially parallel arms slotted longitudinally thereof, a connecting device engaging the slotted parallel arms of said actuating levers and movable longitudinally of the slotted arms, a platen, a platen shifting means, and means under control of said platen shifting means for effecting a movement of said connecting device longitudinally of the slotted arms of said levers. 80
17. In a typewriting machine, the combination of a ribbon vibrator, two angular actuating levers each having a substantially horizontally disposed arm and a substantially vertically disposed arm, a substantially vertically shiftable connection between the vertically disposed arms of said angular levers, and means for shifting said connection. 95
18. In a typewriting machine, the combination of a ribbon vibrator, two angular actuating levers each having a substantially horizontally disposed arm and a substantially vertically disposed arm, a substantially vertically shiftable connection between the vertically disposed arms thereof, means for shifting said connection, a platen, platen shifting means, and means under control of the platen shifting means for shifting said connection relatively to said levers. 100
19. In a typewriting machine, the combination of a shiftable platen, a vibratory ribbon carrier shiftable with said platen and having an unvarying normal relation therewith, an operating lever having a single fulcrum, which fulcrum has the same normal position for both positions of the platen, means for shifting said ribbon carrier 110 through said operating lever, means comprising relatively movable parts for actuating said lever at printing operations, and means for varying the relation between said parts. 115
20. In a typewriting machine, the combination of a platen and platen shifting mechanism, of a vibratory ribbon carrier, a two-part operating connection, means for actuating said connection at printing operations, 120 125 130

6
and means connected with said platen shifting mechanism and operative thereby to vary the relation between the two parts of said connection.

- 5 21. In a typewriting machine, the combination with a platen and platen shifting mechanism, of a vibratory ribbon carrier, an operating connection comprising two parts jointed together, means for constraining said parts to move as one piece in a plurality of fixed relations depending on the shift position of the platen, and means for actuating said parts as one piece at printing operations.
- 10

22. In a typewriting machine, the combination with a platen and platen shifting mechanism, of a vibratory ribbon carrier, a jointed operating connection, means for actuating said connection at printing operation, and means connected with and operative by said platen shifting mechanism to change the relationship between the jointed parts of said connection. 15 20
